UNITED STATES PATENT OFFICE.

SAM H. LIBBY, OF EAST ORANGE, NEW JERSEY, ASSIGNOR TO GENERAL ELECTRIC COMPANY, A CORPORATION OF NEW YORK.

GLIDING SWITCH FOR OVERHEAD MONORAIL TRAMWAYS.

1,078,051.

Specification of Letters Patent.

Patented Nov. 11, 1913.

Application filed October 21, 1912. Serial No. 726,870.

To all whom it may concern:

Be it known that I, SAM H. LIBBY, a citizen of the United States, residing at East Orange, county of Essex, State of New Jersey, have invented certain new and useful Improvements in Gliding Switches for Overhead Monorail Tramways, of which the following is a specification.

This invention relates to switches for use in connection with overhead monorail tramways or runways, on which traveling cranes or hoists are operated. It sometimes happens that the layout of tracks is such as to prevent the use of tongue switches, owing to sharp curves or confined space. The present invention aims to meet this difficulty by providing a switch in which the "points" or connecting sections of rail are secured upon a frame which slides bodily on ways transverse to the tracks. This permits any given rail sections to be alined with any given pair of stub ends of trackage. The frame is shifted by an electric motor, controlled by a limit switch, which can be connected with the trolley conductor by the craneman on an approaching crane and is suitably geared to the motor so that it rotates therewith and breaks the motor circuit only when the gliding switch has reached the position selected by the craneman; all as hereinafter set forth in detail and particularly pointed out in the claims.

In the accompanying drawings, Figure 1 is a top plan view of my improved gliding switch, partly broken away; Fig. 2 is an end view thereof; Fig. 3 is a side elevation of the limit switch, partly in section; Figs. 4 and 5 are sections of Fig. 3 on lines 4-4 and 5-5, respectively, showing the snap action devices of said switch; Fig. 6 shows one end of the traveling crane, and Figs. 7 to 10 are diagrams of the track switch in different positions.

The overhead monorail track or runway is composed of I-beams 1, suitably supported, and the traveling crane or hoist 2 runs on the lower flanges of said beams, being driven preferably by one or more electric motors 3.

In Fig. 1 is shown a crossing of two tracks, the stub ends of the beams 4, 5, 6 and 7 terminating a given distance apart. Transverse I-beams 8 are mounted on the

ends of the track beams, said beams 8 being parallel and serving to support a frame composed of sections of I-beams 9, 10 and 11 connected by an angle iron 12 riveted to their upper flanges. The lower flanges of the beams 9, 10 and 11 are adapted to be alined with those of the track beams 4, 5, 6 and 7 so as to form with them a continuous runway for the crane 2. Rollers 13 are journaled in brackets 14 secured to the beams 9, 10 and 11, and run on the lower flanges of the transverse beams 8, so that the switch frame can glide back and forth thereon. The lengths of the sectional beams 9, 10 and 11 are such that by the movement of the frame they can be brought into alinement with and bridge the spaces between any two of the track ends. Thus in Fig. 7, section 9 connects tracks 5 and 6. In Fig. 8, section 10 connects tracks 6 and 7. In Fig. 9 the same section connects tracks 4 and 5, and in Fig. 10 section 11 connects tracks 4 and 7. With three track sections or switch points, it is therefore possible to make every necessary connection between four stud ends of track.

The mechanism for sliding the switch frame to and fro is a screw 15 rotating in bearings 16 in hangers 17 depending from a channel iron 18 supported by girders 19 resting on the beams 8. The screw is geared to an electric motor 20 supported on one of the girders, and supplied with current through a limit switch 21 which comprises a rotatable drum carrying two sets of segments 22, 23, which are shown developed in Fig. 7, the segments in each set being electrically connected. The segments co-operate with fingers a, b, c, d, e and f, the first and last being connected to the terminals of the field coil 24 of the motor. This coil is made in two sections, one for forward running and one for backward running. The armature 25 is connected between said sections. A brake releasing magnet 26 is in series with the armature. The finger b is connected with short lengths b' of switching conductor adjacent to the trolley conductor for one side of track 4 and the opposite side of track 7. Finger c is connected to conductor c' near one side of track 4 and the same side of track 5. Finger d is connected to conductors d' on similar sides of tracks

6 and 7; and finger *e* is connected to conductors *e'* on opposite sides of tracks 6 and 5.

On each side of the car 27 carried by the crane 2 is a lever 28 having a contact 29 with which the craneman can connect the working track conductor with the short switching conductor on that side of the track. When thus connected, current will flow through the limit switch to the motor and cause the screw to revolve. The screw meshes with a nut 30 mounted on the switch frame, so that the rotation of the screw will traverse the frame in one direction or the other. This direction will always be toward that side of the track on which lies the switching conductor which the craneman has brought into circuit.

Suppose the switch to be standing as shown in Fig. 7. If the crane comes along track 4 and wishes to go to track 5, the craneman operates the lefthand lever to connect the switching conductor *c'* with the track conductor. The motor at once starts moving the switching frame to the left (viewed from track 4) and will continue to move it until the limit switch reaches the position *y'*, when the circuit of finger *e* will be opened, and the motor will stop the gliding track switch in the position shown in Fig. 9; switch point 10 being in line with tracks 4 and 5, so that the crane can proceed. Similarly, it will appear upon tracing the circuits that the four positions *x*, *y*, *y'* and *z* of the limit switch, in which the circuits of the fingers *e*, *d*, *c*, and *b* are respectively broken, correspond with the Figs. 7, 8, 9 and 10 of the drawings with respect to the positions of the gliding switch when said circuits are broken. The switch can be operated in either direction, and by a crane coming in either direction along any one of the four tracks.

It is highly desirable that the gliding switch points be stopped as exactly in line with the track ends as possible. This means that the limit switch must be opened suddenly, and always at the same instant in its movement. The mechanism which accomplishes this will now be described. The spur gear 31 driven by the motor 20 is secured upon a shaft 32 on which are keyed two driving disks 33, 34, the former at one end of said shaft and the latter at a point near the spur gear. Loosely sleeved upon the shaft adjacent to the driving disks are the hubs of two ratchet wheels 35, 36, said hubs being squared to engage with the interior of a drum 37 carrying the switch segments 22, 23. Each ratchet wheel has three teeth 38, two being diametrically opposite and the third half way between them; the opposite segment of 180 degrees being smooth. The teeth on one ratchet wheel face in the opposite direction to those on the other wheel.

Pivoted on the frame of the machine are two detent pawls 39, 40 adapted to engage with said teeth, and each provided with a cam lug 41 on one side. The driving disks have wipers to engage said cams and lift the pawls. These wipers are preferably rollers 42 extending laterally from three arms 43 pivoted to the disks, two diametrically opposite and one midway between on one side, each arm being adjacent to a tooth 38 on the ratchet wheel. An adjusting screw 44 passes freely through each arm and is attached to an adjacent rigid arm 45 projecting from the disk. By operating the lock nuts 46 on the screw, the angular position of each roller can be accurately adjusted, so that it will trip the pawl at just the right instant. A helical spring 47 is coiled on the shaft between the driving disk 33 and the ratchet wheel 35. The ends of the spring extend radially, and between them lie two pins 48, 49, one on the driving disk 33 and the other on the ratchet wheel 35.

The operation is as follows: When the motor 20 starts, it begins also to turn the shaft 32 and the driving disks 33, 34. The pin 48 at once begins to force one end of the spring 47 angularly away from the other end, the particular end so moved depending upon the direction of rotation of the shaft. This puts a tension on the spring, which is resisted by the pin 49; one or the other of the ratchet wheels 35, 36 being locked by its pawl 39, or 40 against rotation in the direction of the shaft. The drum 37 is therefore held stationary until the rotation of the driving disk has proceeded to such a point that the roller 42 adjacent to the tooth 38, which is engaged by its pawl, slides under the cam 41 on said pawl and disengages it from the tooth. By this time the separation of the pins 48, 49 has put considerable tension on the spring, so that when the ratchet wheel is released the drum is given a sudden angular movement through ninety degrees, which brings the pins 48, 49 into radial alignment again, as shown in Fig. 5, in which position the drum is instantly arrested. The parts are so arranged that this new position corresponds with the next in the series *x*, *y*, *y'* and *z* in one direction or the other. If the new position causes the segments on the drum to open-circuit the motor, no further action occurs, because the motor stops and the brake-releasing magnet 26 is deenergized. But if the circuit of the motor still remains closed, the shaft 32 will continue to rotate, again tensioning the spring 47 and again releasing the pawl from the next tooth 38 to permit a second snap of the drum to the next position. The teeth on the idle ratchet wheel simply trail under their pawl.

It will be observed from a comparison of Figs. 4 and 5 that when the pawl 40 is en-

gaging one of its end teeth, the pawl 39 lies on the smooth part of the wheel 35 midway between its end teeth. This is the condition of things when the gliding switch is at one 5 end of its travel and the shaft 32 is about to rotate clockwise in Figs. 4 and 5. At the other end of said travel, the pawl 40 will be lying on the smooth part of its wheel midway between its end teeth, and pawl 39 10 will be engaging tooth 38^a to retard the counter-clockwise rotation of the wheel until properly released.

In accordance with the provisions of the patent statutes, I have described the principle of operation of my invention, together 15 with the apparatus which I now consider to represent the best embodiment thereof; but I desire to have it understood that the apparatus shown is only illustrative, and that 20 the invention can be carried out by other means.

What I claim as new and desire to secure by Letters Patent of the United States is:—

1. The combination with the four stub 25 ends of two monorail tramways, of a gliding switch for connecting them, said switch comprising three rail sections, and means for sliding them transversely into four different connecting positions, the middle section 30 being perpendicular to the line of movement of said switch for connecting in two of said positions directly opposite ends of one or the other of said tramways, and the other two sections being oblique to said line of 35 movement for respectively connecting one end of one tramway with the diagonally opposite end of the other.

2. The combination with the four stub 40 ends of two monorail tramways, of a gliding switch for connecting them in four different positions, an electric motor for operating said switch, a limit switch for stopping said motor in any one of four positions, and means whereby said motor can be started 45 from points adjacent to said stub ends.

3. The combination with the four stub ends of two monorail tramways, of a gliding switch for connecting them in four different positions, an electric motor for op-

erating said switch, and a rotary limit 50 switch for said motor having a snap action and capable of operating in either direction.

4. The combination with the four stub 55 ends of two monorail tramways, of a gliding switch for connecting them in four different positions, an electric motor for operating switch, a rotary limit switch for said motor which comprises a contact carrying drum, ratchet wheels secured thereto, a driving disk adjacent to each wheel, a 60 spring engaged by one of said disks and wheels, and means for tripping the ratchet wheels.

5. The combination with the four stub 65 ends of two monorail tramways, of a gliding switch for connecting them in four different positions, an electric motor for operating said switch, a rotary limit switch for said motor which comprises a contact carrying drum, ratchet wheels secured thereto, a 70 driving disk adjacent to each wheel, a spring engaged by one of said disks and wheels, and means for tripping the ratchet wheels comprising a detent pawl engaging with each ratchet wheel and lifters on said disks 75 for disengaging said pawls.

6. The combination with a gliding switch 80 for monorail tramways, adapted to connect two sets of stub ends of rails in four different positions, of an electric motor for shifting said switch, and a limit switch for stopping said motor which comprises a contact carrying drum having two wheels provided with three ratchet teeth 90 degrees apart, the teeth on one wheel facing opposite to 85 those on the other, detent pawls co-operating with said ratchet wheels, a driving disk adjacent to each wheel and provided with adjustable lifters for said pawls, a helical spring, and pins on one of said disks and 90 wheels engaging the ends of said spring.

In witness whereof, I have hereunto set my hand this 17 day of October 1912.

SAM H. LIBBY.
